UNITED STATES PATENT OFFICE.

SAMUEL W. HILLS, OF JEROME, IDAHO.

ELECTRICAL MASSAGE APPARATUS.

1,234,763.

Specification of Letters Patent. Patented July 31, 1917.

Application filed March 8, 1916. Serial No. 22,948.

To all whom it may concern:

Be it known that I, SAMUEL W. HILLS, a citizen of the United States of America, residing at Jerome, in the county of Lincoln 5 and State of Idaho, have invented certain new and useful Improvements in Electrical Massage Apparatus, of which the following is a specification.

My invention relates to electrical vibratory 10 massage apparatus, and more particularly to an improved type of reciprocating motor adapted for use with alternating or interrupted direct current.

The primary objects of the invention are 15 to provide a reciprocating motor in which means has been devised for regulating and controlling the amplitude of the vibrations, particular regard being had to the facility with which the magnetic fields may be 20 changed with respect to the armature; to provide an armature in combination with an electromagnet, the armature being so arranged that it will vibrate to its maximum and minimum extent without setting up any 25 jerking movements or trepidations; and to provide a massage apparatus of the character described which is extremely simple in construction and arrangement, and which will admit of the device being manufactured 30 at a low figure.

To the accomplishment of the recited objects, and others coördinate therewith the preferred embodiment of my invention resides in that construction and arrangement 35 shown in the accompanying drawings, described in the specification, and embraced within the scope of the appended claims.

In said drawings—

Figure 1 is a perspective view of the device embodying my invention.

Fig. 2 is a central longitudinal section of the apparatus.

Fig. 3 is a detailed perspective view of the armature and the tool holder, and Fig. 45 4 is a transverse section taken along lines 4—4 of Fig. 2.

Generally speaking, my invention comprises a shell formed of two separable sections, one of the shells containing an electromagnet, while the other shell sustains the tool holder which is carried by an armature 50 securely held in proper relation to the said electromagnet at the point of connection of the two sections. The pole or core of the 55 electromagnet is movable relatively to its winding and the armature by means of a

set screw which extends through the bottom of its corresponding shell and its supporting base in easily accessible position. The armature is located in direct vertical alinement 60 with the magnet core and is supported upon diametrically opposite sides by a comparatively thin diaphragm, the tool holder rising vertically from the center of the armature and protruding through the upper shell section. In conjunction with the shell, considered as an entirety, I connect a suitable handle provided with a switch and appropriate electrical connections.

Referring more specifically to the drawings for a more detailed description of my invention, the numeral 5 designates a shell comprising a lower section 6 and an upper section 7, rabbeted and detachably secured together at their adjacent edges by complementary screw threads as at 8. The lower section 6 contains an electromagnet comprising a winding 9 and a central core 10 which is movable relatively to the winding and carries a set screw 11 for effecting its 80 desired adjustment, as will be presently explained. In this connection it will be pointed out that the base of the shell 6 is cut away at 11' to allow for the maximum movement of the core. Furthermore, the 85 winding 9 has its inner wall provided with diametrically opposed vertical keys or flanges 11" engageable with the complementary slots 12' in the core, and the screw 11 is swiveled as at 12" relative to the thin disk 13'. The armature consists of a soft metal disk 12 supported at diametrically opposite points by a spring steel diaphragm 13, the portions of the diaphragm contiguous the armature being of less transverse extent than the outer extremities, the marginal edges of which are adapted to be interposed between the adjacent ends of the shell sections 6 and 7, as at 14. Manifestly, the armature lies in vertical alinement with 90 the axis of the core 10, and rising in the same direction, and preferably carried thereby, is a tool holder 15 protruding through the bushing 16 of the upper shell section. Any suitable conventional type of 100 tool as 17 may be attached to the free end of this tool holder.

The entire shell is supported by an arm 18 which extends from one end of the handle 19, which is provided with the usual electrical connections 20 and a switch 21.

Upon depressing the switch 21 and there-

by energizing the electromagnet, the armature 12 will obviously be caused to rapidly vibrate with respect to its magnetic field which is determined by the position of the core 10. By arranging the said core in close relationship with the armature through the medium of set screw 11, the vibrations of the armature will be very short, while by disposing the core at a greater distance 10 from the armature the same will set up vibrations which are longer in stroke. Regardless of the particular adjustment of the core, it will appear evident that the reciprocations of the armature are only limited by 15 its own inherent resiliency, thereby eliminating absolutely any sudden shocks or metallic abutments.

What I claim is:

1. In an electrical massage apparatus, the combination of a casing, an electromagnet 20 provided with a core, a substantially circular armature of soft metal in operative relation to, and having a diameter coextensive with the diameter of the core, a diaphragm 25 comprising a pair of dove-tail shaped spring steel members carried upon diametrically opposite sides of the armature and arranged medially of and in the same plane with said

armature, a closure for said casing, the outer edges of said diaphragm members being 30 frictionally held between the casing and the closure, and a tool holder mounted upon said armature.

2. In an electrical massage apparatus, the combination of a casing, an electromagnet 35 provided with a core, a substantially circular armature of soft metal in operative relation to, and having a diameter coextensive with the diameter of the core, a diaphragm 40 comprising a pair of dove-tail shaped spring steel members carried upon diametrically opposite sides of the armature and arranged medially of and in the same plane with said armature, a rotund closure for said casing having a central opening provided with a 45 guide bushing, the outer edges of said diaphragm members being frictionally held between the casing and the closure, and a vertical tool holder on the top of said armature and projecting through said bushing. 50

In testimony whereof I affix my signature in the presence of two witnesses.

SAMUEL W. HILLS.
